MIKULAS DRBUL, OF CHICAGO, ILLINOIS

SAFETY DEVICE FOR AEROPLANES

Application filed May 1, 1930. Serial No. 448,934.

This invention relates to a transport aeroplane which has a completely enclosed pilot and passenger cabin, and more particularly to a safety device associated with this type of aeroplane which is manually controlled and semi-automatic in operation to provide quick means for escape of persons from within the aeroplane cabin. It is well known that transport and other cabin planes, when 10 they are disabled in flight, will, with the aid of the pilot, coast to a safe landing if such landing were available. The majority of transport plane accidents and fatalities are caused by the plane either suddenly striking 15 the ground or a permanent object and throwing the passengers against the front portion of the cabin or else by burning the passengers when the plane has struck the earth or object and ignited the oil supply. My invention 20 is designed to provide means to permit ready escape of passengers as well as pilot from a disabled plane while it is in the air and during its descent.

An important object of my invention is the 25 provision of a removable cabin ceiling which is adapted to automatically swing open upon manual operation of means which locks said ceiling in normally closed position.

A further object of my invention is the provision, in an aeroplane body, of overlapping doors forming the top of said body and being adapted to be automatically opened upon actuation of manually controlled locking means.

A further object of my invention is the provision of an aeroplane body having an upwardly and rearwardly inclined panel forming the rear wall of the cabin in association with releasable doors forming the ceiling of said cabin.

A further object of my invention is the provision of an upwardly and rearwardly inclined panel in combination with releasable doors adapted to form an opening in the top of said cabin and an auxiliary door adapted 45 to open in such a way to form an extension of said inclined panel to prevent a person escaping from coming in contact with the tail of the plane.

Another object of the invention is the provision of means adapted to be manually actu-

ated in association with door locking means and adapted to disengage the same to permit automatic opening thereof.

Other and further important objects of this invention will be apparent from the disclosures in the specifications and the accompanying drawings.

This invention in a preferred form is illustrated in the drawings and hereinafter more fully described.

On the drawings:—

Fig. 1 is a side elevational view, with portions cut away, showing the inside of a transport aeroplane and the location of my door locking means, panel and rear auxiliary door.

Fig. 2 is a view of the ceiling of the aeroplane cabin taken from within the cabin and showing the doors in closed and locked position.

Fig. 3 is a view taken from within the cabin of the sloping panel forming the rear cabin wall and showing the top of the open auxiliary door and above.

Fig. 4 is a view taken from above the cabin showing the doors in open position.

As shown on the drawings:—

The reference numeral 1 indicates the cabin of a transport aeroplane having swivel seats 2 secured to the cabin floor. Folded parachutes 3 are removably attached to brackets 4 (not shown) by means of straps 4. That portion of the aeroplane cabin ceiling which is rearward of the front wing comprises doors 5 and 6 which are hinged to the frame of the aeroplane by means of spring hinges 7 and 8 which are sufficiently strong to open said doors when they are unlocked. Said doors 5 and 6 overlap at their adjacent edges and extend rearwardly to a point above the terminus of a sloping wall 9 which forms the rear wall of the passenger cabin and slopes rearwardly toward the top for a purpose which will be apparent hereinafter. Said wall 9 preferably has a door leading to the compartment rearward thereof which may be used for freight or the like.

Door 5 has eyelets 10 secured transversely upon the under surface of the edge adjacent door 6. A sliding rod 11 slidably secured by brackets 12 to door 6 has hooks 13 which

fit into eyelets 10 to lock the doors together in a closed position. Said slidable rod 11 has a transversely extending stud for a purpose which will appear hereinafter and has its 5 front end bent at right angles and extended sidewise.

Near the front end of the plane and preferably near the pilot's seat is a lever 14 pivoted on bracket 15, the latter being secured to 10 the ceiling. Near said bracket 15 are brackets 16 and 17 which are journaled for the reception of a slidable locking rod 18, the front end of which has an aperture adapted to normally hold the bent over end of locking rod 15 11. The rear end of locking rod 18 has a cup-shaped housing 19 integral therewith into which the working end of lever 14 extends. Slide rod 18 has abutment 20 formed on one 20 side thereof which is adapted to slide along the side of irregular-shaped block 21 which is secured to the ceiling wall in such a position that it holds sliding rod 18 and 11 hooked together when the rod 18 is in its extreme 25 rearward position. Pressing against the side 30 of sliding rod 18, opposite block 21 is a leaf spring 22 which is permanently secured to the ceiling wall and has one end pressing against said rod 18. It will be apparent that the block 21 has its irregular side so positioned 35 with respect to the abutment 20 that when the rod 18 is pulled forward the spring 22 presses rod 18 so that the abutment 20 will slide along the receding side of block 21 and the apertured end of rod 18 will be pressed 40 out of engagement with the bent end of rod 11 at the same time rod 18 is pulled forwardly sufficiently to disengage each of hooks 13 from eyelets 10, whereupon the doors will open due to the action of spring hinges 7 and 8.

From the foregoing it will be apparent that the pilot or operator, upon pulling the lever 14 in the direction to pull rods 18 and 11 forwardly, will effect quick opening of 45 doors 5 and 6, which will permit escape of passengers from within the cabin, either with or without the aid of parachutes 3. When a parachute is withdrawn and thrown out of the cabin, partial opening thereof will 50 tend to pull the person upwardly and rearwardly from the cabin when the plane is in a substantially forward and diagonal descent. For this reason and to eliminate the danger 55 of injury from contact with the tail of the plane or other obstructions the wall 9 is made sloping so that the pull of the parachute will pull the person therealong and rearwardly during the plane's descent.

In order to provide an extension for wall 9 60 I provide an auxiliary door 23 having hinges 24 secured immediately rearwardly of the upper edge of wall 9. Said door 23, when opened, will form a substantial extension of the wall 9, the purpose thereof being to cause 65 a passenger who is being pulled upwardly

and rearwardly by a parachute as above stated to be pulled sufficiently high above the top of the plane body to clear the vertical rudder of the plane.

To effect automatic opening of said auxiliary door 23 I provide a toggle 25, one end of which is secured to the inside of the plane and the other end being secured to said door 23. A spring 26 having one end secured to the cabin ceiling and its other end secured to the center of said toggle is adapted to open said door to the dotted line position shown in Fig. 1. To provide locking means for said auxiliary door 23 I provide a slidable rod 27 which is slidably secured to said door by means of brackets 28 and has its forward end bent to form a hook 29 which is adapted to engage a transverse lug 30 on the rear end of locking rod 11. The rear end of rod 27 is adapted to slide into a receiving catch 31 secured in the upper wall of the plane body when the door is closed. The rod 27 also has a transverse cross-bar 32 forming a handle for use when it is desired to open the door 23 manually, one end of said cross-bar 32 protruding through a slot in the door 23 to permit convenient access thereto. The transverse hook 29 of rod 27 is so constructed that when rod 27 is pushed forwardly and the door 23 is opened, it will move out of engagement with the lug 30 of locking rod 11. This construction permits opening of the door 23 independent of doors 5 and 6, which is highly desirable for freight or baggage loading.

I am aware that many changes may be made and numerous details of construction may be varied through a wide range without departing from the principles of this invention, and I therefore do not purpose limiting the patent granted hereon otherwise than necessitated by the prior art.

I claim as my invention:

1. In an aeroplane, doors hingedly attached thereto and normally forming the cabin ceiling; said doors having their adjacent edges overlapping each other, springs on said doors imparting an opening stress thereto; eyelets in the lower of said overlapping doors; a slidable rod on the upper door having hooks adapted to engage said eyelets and having an extended forward end terminating in a hook, a lever pivoted in said ceiling cabin; a rod releasably connecting said lever and the door locking rod, and a spring normally pressing said connecting rod against said block, said spring being adapted to push said connecting rod against said block, said spring being adapted to push said connecting rod out of engagement with said door locking rod when said connecting rod reaches a predetermined point in its forward movement.

2. In combination with an aeroplane, overlapping doors hingedly secured thereto forming a portion of the cabin roof; releasable

- locking means adapted to lock said doors in closed position; spring means adapted to open said doors when they are unlocked; a manually operable lever fulcrumed in the 5 forward part of said plane; a connecting rod between said releasable door locking means and said lever adapted to be disengaged from said door locking means to permit automatic opening of said doors, and a panel forming 10 a rear cabin wall and terminating adjacent the rear ends of said doors.
3. In combination with an aeroplane, overlapping doors hingedly secured thereto forming a portion of the cabin roof; releasable 15 locking means adapted to lock said doors in closed position; spring means adapted to open said doors when they are unlocked; a manually operable lever fulcrumed within said plane; a rod having one end "pivotally" 20 secured to said lever and its other end terminating in a hook normally releasably engaging said door locking means, and means adapted to disconnect said connecting rod hook from said door locking means.
- 25 4. In combination with an aeroplane, overlapping doors hingedly secured thereto forming a portion of the cabin roof; releasable locking means adapted to lock said doors in closed position; spring means adapted to 30 open said doors when they are unlocked; a manually operable lever fulcrumed within said plane; a rod having one end "pivotally" secured to said lever and its other end terminating in a hook releasably engaging said 35 door locking means, a block disposed adjacent the hooked end of said rod, and a spring secured to the aeroplane surface adapted to press said rod end out of engagement with said door locking means when said connecting rod is moved from its position adjacent said block.
- 40 5. In combination with an aeroplane, overlapping doors hingedly secured thereto forming a portion of the cabin roof; releasable 45 locking means adapted to lock said doors in closed position; spring means adapted to open said doors when they are unlocked; a manually operable lever fulcrumed within said plane; a rod having one end "pivotally" 50 secured to said lever and its other end terminating in a hook normally releasably engaging said door locking means, a spring adapted to disengage said connecting rod from said door locking means when said rod is moved 55 forwardly; and a panel forming a rear cabin wall, the top thereof sloping rearwardly and upwardly and terminating adjacent the rear ends of said doors.
- 60 6. In combination with an aeroplane, overlapping doors hingedly secured thereto forming a portion of the cabin roof; releasable locking means adapted to lock said doors in closed position; spring means adapted to open said doors when they are unlocked; a 65 manually operable lever fulcrumed within
- said plane; a rod having one end "pivotally" secured to said lever and its other end terminating in a hook normally releasably engaging said door locking means, a spring adapted to disengage said connecting rod from said door locking means when said rod is moved forwardly; a panel forming a rear cabin wall, the top thereof sloping rearwardly and upwardly and terminating adjacent the rear ends of said doors, an auxiliary door in the top of said plane hinged adjacent the upper portion of said sloping panel and adapted to form an extension of said panel when in open position.
- 70 7. In an aeroplane, doors hingedly attached thereto and normally forming the cabin ceiling; said doors having their adjacent edges overlapping each other, springs on said doors imparting an opening stress thereto; eyelets in the lower of said overlapping doors, a slideable rod on the upper door having hooks adapted to engage said eyelets and having an extended forward end terminating in a hook, a block on said aeroplane top having an enlarged portion and a reduced portion forming a shoulder and adapted to serve as a guide and stop for said slideable rod, a manually operable lever having its fulcrum adjacent the cabin ceiling and extending thereabove.
- 75 80 85 90 95 100 105 110 115 120 125 130
- In testimony whereof I have hereunto set my hand this 15th day of April, 1930.
- MIKULAS DRBUL.
